CLAIM

The ornamental design for a signal booster case, as shown and described.

DESCRIPTION

FIG. 1 is a top perspective view of the presently claimed design.

FIG. 2 is a side view of the presently claimed design.

FIG. 3 is an opposite side view of the presently claimed design.

FIG. 4 is a front view of the presently claimed design.

FIG. 5 is a rear view of the presently claimed design.

FIG. 6 is a top view of the presently claimed design.

FIG. 7 is a bottom view of the presently claimed design; and,

FIG. 8 is a bottom perspective view of the presently claimed design.

1 Claim, 6 Drawing Sheets
